UNITED STATES PATENT OFFICE.

LYMAN C. JOSEPHS, JR., AND LEVERETT H. CUTTEN, OF ALLENTOWN, PENNSYLVANIA, ASSIGNORS TO INTERNATIONAL MOTOR COMPANY, OF NEW YORK, N. Y., A CORPORATION OF DELAWARE.

COOLING SYSTEM.

Application filed July 7, 1922. Serial No. 573,339.

To all whom it may concern:

Be it known that we, LYMAN C. JOSEPHS, Jr., and LEVERETT H. CUTTEN, a citizen of the United States, and a subject of the King 5 of Great Britain, respectively, both residing in Allentown, in the State of Pennsylvania, have invented certain new and useful Improvements in Cooling Systems, of which the following is a specification, reference being had to the accompanying drawings, 10 forming a part hereof.

This invention relates to a cooling system for motor vehicles and has for its general object to bring into effective relationship 15 elements which themselves are old for the most part and have been recognized as efficient but which in their nature have not been susceptible of combination into an efficient unitary structure. More particularly, 20 the invention seeks to provide in a cooling system for the use of a multi-bladed fan on the flywheel of the motor to be cooled, a fan scroll in association therewith and radiator sections above the fan and at the sides of the 25 radiator structure which receive a uniform distribution of cooling currents thereover and lend themselves to ready cleaning. A multi-bladed fan has long been recognized as an efficient unit but it has not lent itself 30 to convenient use in a radiator structure since no practical means have been devised for bringing about distribution of the air over the radiator tubes or for insuring operation of the fan in its maximum capacity. 35 In accordance with the present invention a fan scroll has been brought into co-operative relation to such a fan in a radiator structure for the purpose of securing the greatest volume and velocity of air and means have 40 been provided for dispersing the air which is projected from this housing uniformly over the cooling sections at opposite sides of the radiator structure. By the improvements herein indicated it becomes possible also, in 45 one embodiment, to employ straight finned radiator tubes and to associate therewith unitary caps at the top of the tube sections which may be removed to expose the upper ends thereof and facilitate cleaning. 50 The invention will be described more particularly with reference to the embodiment

illustrated in the accompanying drawings wherein:

Figure 1 is a rear view partly in elevation and partly in section of a radiator structure 55 embodying the improvements.

Figure 2 is a view partly in elevation and partly in vertical section of the cooling system illustrated in Figure 1.

Figure 3 is a view in plan parts being 60 broken away in the interest of clearness.

The improved radiator structure may be mounted on the side frame members *a* of a motor vehicle and include an upper reservoir *b* lower tank sections *c*, *d*, connected by 65 a pipe *e* and in the preferred embodiment, as illustrated, vertically disposed straight finned radiator tubes *f* arranged in sections at opposite sides of the radiator structure and extending between the upper reservoir 70 *b* and the respective lower tanks *c*, *d*. As shown most clearly in Figure 3 the upper reservoir *b* is provided adjacent its ends with removable caps *b'* which overlie the upper ends of the tubes *f*. When the caps 75 *b'* are removed, as by loosening their retaining bolts *b* the straight finned radiator tubes *f* have their upper ends exposed so that cleaning is greatly facilitated. In addition to the parts of the radiator described 80 there is included in the improved cooling system, in co-operative relation therewith, a multi-bladed centrifugal fan *g* which may be bolted on the flywheel *h* of the motor to be cooled. The axis of the flywheel indicated at *h'* is, of course, considerably below the radiator structure and it is a problem to employ a fan of multi-bladed type on the flywheel for the purpose of cooling the tubes 85 *f* in the radiator sections. However, such a type of fan is extremely efficient provided it can be properly employed. In accordance 90 with the present invention there is provided for the fan a fan scroll *i* formed, for convenience, as a generally semi-cylindrical casting which may be bolted to the under-part of the flywheel housing as by means of bolts *i'*. This housing conforms generally to the lines of the spiral channel in the fan scroll *i*. For instance, as shown in Figure 1 one side of the housing *k* for the flywheel is 95 curved to conform to the periphery of the

fan and there is comparatively small clearance between the fan and this curved portion k . By the construction and arrangement of parts described and considering the 5 fan to be rotating in a counterclockwise direction as viewed in Figure 1 it is evident that the surrounding air entering into the housing principally through the open rear face k' thereof will be picked up by the fan 10 and crowded by the blades thereof into the spiral channel along the fan scroll. The maximum volume of air may be crowded by the blades into the housing the eccentricity thereof with respect to the fan permitting 15 maximum capacity. The air currents discharged upwardly by the fan at the right side thereof as viewed in Figure 1 are confined between the front and rear walls k^2 of the radiator structure. Having secured, as 20 described, a maximum volume of air circulating with a maximum velocity and created with the maximum efficiency, which is to say, with a minimum wastage of power, it becomes a further problem in a structure of 25 this character to disperse or direct the air currents uniformly over the tubes f in the radiator sections which, as pointed out above, are disposed at opposite sides of the upper reservoir b . The tendency of these 30 currents as will be understood from Figure 1 is to take a path generally towards the tubes at the left of the structure. The proper dispersion and direction are secured in the improved construction by means of baffles 35 which are so disposed as to separate the air and deflect it in equal volume towards the two sections of the tubes. At the upper part of the space between the front and rear walls k^2 of the radiator structure there 40 is disposed a generally V shaped baffle which presents diverging plates l , l' . These plates may be secured to the front and rear walls k^2 and may intersect along such a line l^2 as will insure proper distribution of the air. 45 Since the trend of the air currents is towards the left as viewed in Figure 1 the plate l will extend beyond the center line m which passes through the radiator and the axis h' of the flywheel h so as to intercept a 50 greater proportion of such currents as they pass upwardly and tangentially from the fan blades. In this way, a sufficient volume of air is deflected by the baffle l towards the tubes in the right-hand section. However, 55 it is true that some of the air currents will pass from the fan along substantially vertical paths. Such currents impinging upon the horizontal wall of the reservoir b tend to retard movement towards the tubes in the 60 right-hand section and for this reason a curved baffle n is mounted between the front and rear walls k^2 and in such relation to the fan and to the baffle l as to intercept and deflect all air currents which would not be 65 intercepted and deflected by the baffle l . The

form of baffle n is such as to deflect the air towards the tubes f in the right-hand section.

By the combination of parts described, disposed in the novel relationship appearing 70 herein, there is accomplished an efficient cooling system in which elements of recognized usefulness are employed to advantage. The straight finned tubes are so disposed as to be readily accessible for cleaning. Their 75 disposition is not such as to prevent their sufficient cooling. A multi-bladed fan is mounted on the flywheel and the disposition thereof with respect to the radiator structure proper does not prevent its efficient use 80 by reason of the association therewith of a fan scroll which insures the creation of air currents of maximum volume and velocity. The interposition of appropriate baffles between the fan housing and the radiator tubes 85 effects a dispersion and direction thereof in an efficient manner and in equal volumes uniformly over all of the tubes grouped in the two sections at opposite sides of the reservoir b .
90

While the invention has been described with reference to the employment of straight finned radiator tubes, it has been found that the elements function to equal advantage where the radiator sections are of a cellular 95 type core, or a finless tube core.

What we claim is:

1. In a cooling system for motor vehicles in combination with a tank, radiator sections disposed vertically and connected with 100 said tank adjacent opposite ends thereof, a multi-bladed fan mounted on the flywheel and disposed generally below and between the two sections, and means to deflect the air from the fan in substantially equal volumes 105 over said two sections.

2. In a cooling system for motor vehicles in combination with water reservoirs, sections of tubes extending therebetween, a multi-bladed fan mounted on the flywheel 110 and disposed generally below and between the sections of tubes, a fan scroll for the fan and directing the air currents generally upward, front and rear walls extending between the sections of tubes to confine said 115 air, and baffles disposed between said walls to deflect the air in equal volume over the two sections of tubes.

3. In a cooling system for motor vehicles in combination with a tank, radiator sections 120 disposed vertically and connected with said tank in spaced relation, a multi-bladed fan disposed generally below and between said sections, and means to deflect the air from the fan over said sections in substantially 125 equal volume.

This specification signed this 5th day of July, A. D. 1922.

LYMAN C. JOSEPHS, JR.
LEVERETT H. CUTTEN.
